US00D961915S

(12) **United States Design Patent** (10) **Patent No.:** **US D961,915 S**
(45) **Date of Patent:** **** Aug. 30, 2022**

(54) **HOLDER WITH DEVICE**

(71) Applicant: **Magic Leap, Inc.**, Plantation, FL (US)

(72) Inventors: **Shigeru Natsume**, Weston, FL (US);
Sebastian Gonzalo Arrieta Gunther,
Fort Lauderdale, FL (US)

(73) Assignee: **Magic Leap, Inc.**, Plantation, FL (US)

(**) Term: **15 Years**

(21) Appl. No.: **29/723,303**

(22) Filed: **Feb. 5, 2020**

(51) LOC (13) Cl. **03-01**

(52) U.S. Cl.

USPC **D3/218; D14/356**

(58) **Field of Classification Search**

(57) **CLAIM**

The ornamental design for a holder with device, as shown and described.

DESCRIPTION

FIG. 1 is a top perspective view of the holder with device.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines illustrate environmental features that form no part of the claimed design.

1 Claim, 5 Drawing Sheets
